[57] CLAIM

The ornamental design for a fisherman's tool, as shown and described.

DESCRIPTION

FIG. 1 is a top plan view of a fisherman's tool embodying my design; it shows the face of the tool having its lower left corner tapered.

FIG. 2 is a left elevational view thereof.

FIG. 3 is a front elevational view thereof.

FIG. 4 is a bottom plan view thereof.

FIG. 2

FIG. 1
